UNITED STATES PATENT OFFICE.

ADOLPH DE CLAIRMONT, OF LOS ANGELES, CALIFORNIA.

APPARATUS FOR GENERATING RADIUM WATER.

Application filed February 16, 1926. Serial No. 88,651.

This invention relates to an improved apparatus for generating radium water and has as its primary object to provide an apparatus by the employment of which, water, introduced into the apparatus, may become impregnated with radium emanations from the radium-bearing material within the apparatus, to a maximum degree. It is a well known fact that radium emanations contained in water will be rapidly dissipated unless the impregnated water is maintained under pressure. Even under this condition, the emanations will be discharged from the water and be condensed or deposited on the surfaces of the container which are above the water level. Therefore, it is obvious that if these deposited emanations can be again returned to the water, impregnation of the water to a maximum degree will be effected, and the present invention contemplates the provision of an apparatus whereby this result may be obtained.

Another object of the invention is to provide an apparatus for generating radium water so constructed and capable of operation in such a manner as to permit of recovery of a maximum amount of the emanations which have escaped from the water within the container of the apparatus and which have condensed or accumulated upon the walls of the container above the water level, so that the apparatus will possess maximum efficiency and a thoroughly impregnated fluid may be obtained therefrom.

Another object of the invention is to provide a novel and highly efficient radium emanation bearing unit or medium which will insure of thorough impregnation of the water within the container of the apparatus.

Another object of the invention is to so construct the radium-emanation bearing unit or medium and the portion of the apparatus with which it is associated, that the said unit may be removed and another unit substituted therefor, thus permitting of the employment, in the apparatus, of radium-bearing materials of different strengths.

In the accompanying drawings:

Figure 1 is a view in front elevation of the apparatus embodying the invention, a part being shown in section.

Figure 2 is a vertical front to rear sectional view through the apparatus, the container being in generating position. 55

Figure 3 is a horizontal sectional view taken substantially on the line 3—3 of Figure 2, looking in the direction indicated by the arrows.

Figure 4 is a detail vertical transverse sectional view taken substantially on the line 4—4 of Figure 2, looking in the direction indicated by the arrows, and illustrating in detail the radium-emanation bearing medium of the apparatus. 60 65

Figure 5 is a fragmentary sectional view illustrating a slight modification of the invention.

The apparatus embodying the invention includes a container which is indicated in general by the numeral 1 and which is supported upon a stand indicated in general by the numeral 2 and comprising a base 3 and spaced upstanding uprights 4, the container being provided with trunnions 5 and 6 upon its outer side located at diametrically opposite points and nearer one end of the container than the other, the said trunnions being journaled in bearing openings in the upper ends of the uprights 4. Inasmuch as the trunnions 5 and 6 are located nearer one end of the container than the other and which end will be considered, in the following description, as the upper end, the container will be overbalanced and tend to normally assume the position shown in Figure 2 of the drawings. 70 75 80

In order that the container may be swung back and forth upon its trunnions and completely rotated, a crank handle 7 is secured to the projecting end of the trunnion 6, and the purpose of thus imparting motion to the container will presently be fully explained. It may be stated at this point that when the container assumes the position shown in Figure 2, it is 90 in what may be termed the generating position and when it is inverted as shown in Figure 1, it is in position for the delivery therefrom of the impregnated water, and in order that the container may be held in this 95 latter position while the impregnated water is being drawn therefrom, the wall of the container is preferably formed, opposite one of the uprights 4, with a boss 8 having a 100

socket 9 therein to accommodate the end of a locking plunger 10 which is slidably fitted through the said upright and which is yieldably held, by a coil spring 11 thereon, in position to engage in the said socket 9, the outer end of the plunger being provided with a finger piece 12 whereby it may be retracted to permit of return of the container to generating position. A faucet 13' of any ordinary type is secured in an air-tight manner in the wall of the container near the said upper end thereof and, when the container is in the delivering position shown in Figure 1 of the drawings, is so positioned as to permit of water being drawn from the container into a glass.

The container 1 may be of metal or any other material found suitable for the purpose and the same is of cylindrical form and comprises a cylindrical wall 13, an upper end wall 14, and a bottom 15, and the container is preferably initially formed in two sections threaded together as at 16, a gasket 16' being arranged at the threaded connection to render the same air-tight. A lining 17 of porous material such as porcelain, may be applied to the inner surface of the upper section, including the cylindrical wall portion of said section as well as the top or upper end wall 14, and by separating the sections, the lining may be cleaned as required. It has been found that porous material of this nature will more readily accumulate and retain the emanations which are deposited thereon than will a non-porous surface and, therefore, inasmuch as, in the generating position of the container shown in Figure 2, the portion of the container which is provided with the lining 17 is above the level of the water within the container, the radium emanations which escape from the water during the process of generation, will be deposited upon the surface of the said lining and retained thereby.

The numeral 18 indicates in general a unit which carries the radio-active material and this unit comprises a metal base 19 which is of flat circular form and threaded at its periphery as at 20 to engage threads upon the wall of an opening 21 formed in the bottom 15 of the container and located centrally of said bottom. The under side of the base 19 is preferably formed with a diametric groove 22 for the application of a screw driver whereby the base may be threaded into place and removed, or any other means may be provided for effecting this result. The upper side of the base is formed with a shallow cylindrical recess 23, and the lower end of a cylinder 24 is fitted into this recess and secured in place in any suitable manner. The cylinder 24 is preferably of porcelain or other porous material and the wall thereof is relatively thin so that it may be readily permeated by the

water within the container. The numeral 25 indicates a lining of radio-active material such for example as uranium ores suitably concentrated, or radium bromides or chlorides, which lining is applied to the inner surface of the cylinder 24 and extends entirely over the said surface as clearly shown in Figure 4 of the drawings. At this point it will be evident that radio-active units bearing radio-active material of different strengths may be readily substituted one for another. The cylinder 24 is, of course, open at its top so that water introduced into the container will fill the cylinder as well as surround the same and, when the container is in the generating position shown in Figure 2 of the drawings, the radium emanations will impregnate the water within the container and these emanations will be dissipated and deposited upon the lining 17. Inasmuch as the container is closed in an air-tight manner during the period of generation, none of the emanations will escape to the atmosphere.

In order that water may be introduced into the container of the apparatus, the top wall 14 of the container is provided with an interiorly threaded neck 26 into which is removably threaded a closure plug 27, a packing gasket 28 being preferably interposed between the upper end of the neck and the under side of the head of the said plug so as to provide an air-tight fit between the parts.

The numeral 29 indicates in general a pressure check valve which may be of any of the well known types and which is secured in an opening in the top wall 14 of the container in an air-tight manner and provides means whereby carbonic acid gas or air under pressure, or carbonated water, may be introduced into the container, primarily to establish pressure within the container but also for the purpose of either carbonating the water within the container or aerating the same.

In the use of the apparatus, the container 1 being in the position shown in Figure 2, the closure plug 27 is removed and, the valve or faucet 13' being open, water is introduced into the container until it appears at the said faucet, whereupon the faucet is closed and the plug 27 is replaced. Carbon dioxide gas, carbonated water, or air, under pressure, is then introduced into the container by way of the check valve 29 until the desired pressure has been established in the container, and this may be determined by an ordinary pressure gage applied to the valve. The container is then permitted to remain in the position shown in Figure 2, for a sufficient length of time to permit the water to become impregnated with the radium emanations from the radio-active material 25 within the cylinder 24, after which the container

is rocked or swung backwardly and forwardly through the medium of the crank handle 7, or the container may be so swung at intervals during the period of generation. 5 After the water has become impregnated with the radium emanations, the emanations will be dissipated and will accumulate upon the lining 17 and any exposed portion of the inner surface of the wall 13 of the container. 10 The container is inverted to the position shown in Figure 1 of the drawings, and, if desired, prior to being moved to this position, may be completely rotated several times through the medium of the crank handle so 15 as to cause the water within the container to wash or surge over the lining 17 and effect further impregnation of the water with the radium emanations. It will be understood that where carbonic acid gas is introduced under pressure into the container, the agitation of the water in the container resulting from the previously described movement of the container, will effect absorption of the gas by the water, and whether the 20 gas referred to or air is introduced under pressure, the effect will be to disturb the radio-active material of the unit 18 and force the radium emanations into the water. Likewise, when the container is rocked or re- 25 volved, the radium emanations which have been deposited on the wall of the container will be taken up by the water.

When it is desired to withdraw the radium impregnated water from the container, the 30 container is rotated to the position shown in Figure 1 of the drawings, and the faucet 13' may then be opened to permit of the discharge of the water, it being understood that the pressure which has been established 35 within the container serves to effect delivery of the water without the necessity of the provision of any vent opening in the container.

The lining 17 is a permanent lining and it 40 will, of course, be desirable to introduce into the container of the apparatus filtered water so that there will be no likelihood of the accumulation of impurities upon the surface of the lining.

45 Figure 5 of the drawings illustrates a slight modification of the invention in which the sections of the container may be connected by threads 30 or in any other manner, and a continuous bead 31 of solder applied 50 to the outer side of the container to extend entirely around and close the joint between the sections in a gas-tight manner, it being understood that by scraping off the bead 31, the sections may be readily separated.

60 Having thus described the invention, what I claim is:

1. In apparatus for generating radium water, a container, means supporting the same for free swinging movement from a 65 normal position to an inverted position,

whereby it may be swung and rotated as well as inverted, a valved outlet for the water at the normally upper portion of the container, and means within the container at the normally lower portion thereof for the retention 70 of radio-active material.

2. In apparatus for generating radium water, a container, means supporting the same near one end for free swinging movement whereby the container will normally 75 occupy one position, and whereby the container may be swung to an inverted position, a valved outlet for the water at the normally upper portion of the container, and means within the container at the normally lower portion thereof for the retention of radio-active material.

3. In apparatus for generating radium water, a container, means for supporting the container near one end for free swinging 85 movement from a normal position to an inverted position, means for holding the container in the latter position, a valved outlet for the water at the normally upper portion of the container, and means within the container at the normally lower portion thereof for the retention of radio-active material. 90

4. In apparatus for generating radium water, a container, means supporting the container near one end thereof for free 95 swinging movement whereby it will normally assume one position, a valved outlet for the water at the normally upper portion of the container, a radium-emanation accumulating lining within the said normally upper portion of the container, and means within the container at the normally lower portion thereof for the retention of radio-active material. 100

5. In apparatus for generating radium 105 water, a container, means supporting the same for free swinging movement from a normal position to an inverted position, a valved outlet for the water at the normally upper portion of the container, a valved inlet for a fluid under pressure at said normally upper portion of the container, and means within the container at the normally lower portion thereof for the retention of radio-active material. 110

6. In apparatus for generating radium water, a container, means supporting the same for free swinging movement from a normal position to an inverted position, a valved outlet for the water at the normally upper portion of the container, a valved inlet for a fluid under pressure at said normally upper portion of the container, means at the said normally upper portion of the container for permitting the introduction of water into the container, and means within the container at the normally lower portion thereof for the retention of radio-active material. 120

7. In apparatus for generating radium 125 water, a container, means supporting the same for free swinging movement from a normal position to an inverted position,

water, a container, means supporting the container near one end thereof for free swinging movement whereby it will normally assume one position, a valved outlet for the water at the normally upper portion of the container, a radium-emanation accumulating porous lining within the said nor-

mally upper portion of the container, and means within the container at the normally lower portion thereof for the retention of 10 radio-active material, the said valved outlet opening through the said lining.

In testimony whereof I affix my signature.

ADOLPH de CLAIRMONT. [L. s.]
